NECKTIE HOLDER

Henry W. Youngquist, Parkersburg, W. Va., assignor to Parkersburg Specialty Company, Parkersburg, W. Va., a partnership composed of Henry W. Youngquist and E. C. Hartman

Application June 15, 1938, Serial No. 213,913

6 Claims. (Cl. 211—113)

This invention relates to a necktie holder.

The invention has for its object to provide, in a manner as hereinafter set forth, a device of the class referred to for detachably suspending neckties firmly in position and in full view to enable one to quickly select the tie desired.

A further object of the invention is to provide, in a manner as hereinafter set forth, a device of the class referred to capable of being used not only by one for holding his ties, but also in haberdasheries for displaying and suspending of neckties.

A further object of the invention is to provide, in a manner as hereinafter set forth, a device of the class referred to for locking thereto the neckties held thereby and suspended therefrom.

A further object of the invention is to provide, in a manner as hereinafter set forth, a device of the class referred to including a housing means having arranged therein and depending therefrom shiftable, resilient means coacting with the housing forming means for latching neckties to the latter in depending relation thereto, and with said resilient means capable of being conveniently shifted, when desired to release a selected necktie.

Further objects of the invention are to provide, in a manner as hereinafter set forth, a necktie holder which is simple in its construction and arrangement, strong, durable, compact, readily assembled, distinctive and pleasing in appearance, conveniently operated for attaching and removing neckties thereto and therefrom, and comparatively inexpensive to manufacture.

Embodying the foregoing objects and others which may hereinafter appear, the invention consists of the novel construction, combination and arrangement of parts as will be more specifically referred to and illustrated in the accompanying drawings wherein is shown embodiments of the invention, but it is to be understood that changes, variations and modifications may be resorted to which fall within the scope of the invention as claimed.

In the drawings:

Figure 1 is a front elevation of a necktie holder in accordance with this invention.

Figure 2 is a top plan view thereof,

Figure 3 is an elevation looking towards one end of the holder,

Figure 4 is a section on line 4—4, Figure 2,

Figure 5 is a section on line 4—4, Figure 2, showing a necktie latched to the holder,

Figure 6 is a section on line 6—6, Figure 2,

Figure 7 is a section on line 7—7, Figure 1,

Figure 8 is a fragmentary view in end elevation of a modified form of necktie holder in accordance with this invention.

Figure 9 is a fragmentary view in front elevation of the holder shown in Figure 8,

Figure 10 is a section on line 10—10, Figure 9,

Figure 11 is a section on line 11—11, Figure 10,

Figure 12 is a section on line 12—12, Figure 10,

Figure 13 is a section on line 13—13, Figure 11,

Figure 14 is a fragmentary view of the lock 10 shaft and key socket.

Figure 15 is an elevation of the key employed with the modified form shown in Figures 8 and 9, and

Figures 16, 17, 18 and 19 are vertical sectional views of still other modified forms.

With reference to Figures 1 to 7 the holder shown thereby is of the suspendible type and includes an open top and open bottom housing 1 formed of a vertical rear wall 2, a front wall 3 20 inclining inwardly from its bottom to its top and a pair of side walls 4, 5 which decrease in width from their bottoms to their tops. The wall 2 is of greater height than the other walls of the housing and depends below the bottoms of the 25 walls 3, 4, 5. The top edge of wall 2 is arranged below the top edges of walls 4, 5. Preferably the walls 3, 4 and 5 will be formed of a single piece of any suitable material and with the walls 4, 5 of less thickness than wall 3. The wall 2 30 preferably will be of greater thickness than the walls 3, 4, 5 and it is formed of any suitable material. The wall 2 is arranged between and has its outer face flush with the rear edges of walls 4, 5. The wall 2 is secured to the walls 4, 5 by 35 the holdfast means 6.

The inner face of the wall 3 in proximity to its bottom edge is formed lengthwise thereof with a substantially concave groove 7. The walls 4, 5 are provided with openings 8 in proximity to 40 their top edges. The front face of wall 3 has attached thereto a mirror 9.

Secured upon the top edge 10 of wall 2, extending towards the inner face of wall 3 and depending from the open bottom of housing 1 is 45 a series of spaced resilient latching members or elements 11 of strap-like form and each is of the same construction. Each member 11 includes a horizontally disposed hanger part 12, a vertically disposed combined finger and thumb gripping 50 part 13 and an upstanding latching part 14 which inclines rearwardly from the upper end of part 13 to the inner end of part 12. The lower end terminal portion 15 of the part 14 is outwardly directed and is of convexo-concave contour 55.

whereby the part 13 will be inset relative to wall 3. The portion 15 constitutes a clamp and is normally seated in the groove 7. The parts 12 of the elements 11 are mounted in spaced relation upon the top edge 10 of wall 2. The parts 12 are secured on edge 10 by the holdfast means 15. The parts 14 of elements 11 extend from wall 2 to wall 3. The portion 15 when active coacts with the wall of the groove 7 for releasably clamping a necktie 16 against and in depending relation with respect to the inner face of wall 3. When connecting the necktie to the holder, the portion 15 of an element 11 is shifted rearwardly from and held in spaced relation with respect to groove 7, a part of the necktie is inserted between portion 15 and wall 3, after which member 11 is released and springs against the part aforesaid of the necktie whereby a portion of the latter will enter groove 7 resulting in the detachable clamping of the necktie to the holder. The material from which the elements 11 are formed is of the desired resiliency to tightly clamp the necktie to the holder.

A bail 16 is loosely coupled to the walls 4, 5 for suspending the housing. The bail 16 is constructed from a single length of wire of the desired gauge. The wire is bent to form a pair of oppositely downwardly inclined portions 17 merging at their lower ends into a pair of oppositely disposed hook portions 18 for passage through the openings 8 in walls 4, 5 for coupling the housing to the bail. The upper ends of the portions 17 merging into a pair of vertically disposed portions 19 merging at their upper ends into each other. The portions 19 for a part of their length are maintained in inner sidewise abutting relation by a collar 20 which surrounds said parts. Above the collar 20 the portions 19 are bent in a manner to form a loop 21 constituting a coupling for connecting the holder to a suspension therefor not shown.

With reference to Figures 8 to 15 the form of necktie holder illustrated is primarily for use in haberdasheries for displaying neckties and includes means for locking the ties to prevent their surreptitious removal. The form is what may be termed the supported type and is for mounting on a counter, show case or other support. It not only includes a locking means for the neckties, but also a means for latching them in suspended position in a manner whereby a purchaser may view and examine them when making a selection.

The holder shown by Figures 8 to 15 is generally indicated at 22 and includes an open top and bottom rectangular housing formed from a pair of oppositely disposed U-shaped sections set up in a manner to provide a pair of side walls 23, 24, a front wall 25 and a rear wall 26. The walls 25, 26 are disposed at opposite inclinations and extend at an inward inclination from their lower to their upper ends. The sections of the housing are formed of any suitable material, preferably stamped from a web of sheet metal of the desired gauge. Arranged within, centrally of and disposed lengthwise of the housing is a vertically disposed partition 27 of less height than the housing walls. The partition divides the housing into a pair of open top and bottom compartments 28, 29 which decrease in width from the bottom of the housing to the top of the latter. The partition 27 at its bottom is flush with the bottom of the housing and at its top arranged below the upper edges of the housing walls. Those parts of the sections of the housing which provides the

side walls 23, 24 are secured against the side edges of the partition 27 by the holdfast means 30.

Each side wall in proximity to its bottom is formed with a pair of oppositely disposed semi-circular protuberances 31, 32. The walls 25, 26 in proximity to their bottoms are formed with offset portions 33, 34 of convexo-concaved cross section. The portion 33 at its ends merges into and is flush with the outer edges of the protuberance 31. The portion 34 at its ends merges into and is flush with the edge of the protuberances 32. The protuberances 31, 32 and portions 33, 34 coact to form lengthwise of the inner faces of the walls 25, 26 grooves 35, 36 respectively closed at their ends.

Arranged within and depending from the compartment 28 is a series of spaced resilient shiftable latching members 37, and arranged within and depending from the compartment 29 is a series of spaced resilient shiftable latching members 38 which are oppositely disposed with respect to the latching members 37. Secured upon the top edge 39 of partition 27, is a series of spaced couplers 40. Holdfast means 41 are employed for securing the couplers 40 on the partition 27. Each coupler at one end merges into the upper end of a member 37 and at its other end into the upper end of a member 38. The members 37, 38 are of strap-like form. The members 37 normally extend from the upper end of the partition 27 to the wall 25 and permanently depend from the bottom of the housing. The members 38 normally extend from the upper end of partition 27 to the wall 26 and permanently depend from the bottom of the housing. The members 37, 38 are of like form. Each member 37 consists of an outwardly inclined downwardly disposed upper end part 42, an outset intermediate part 43 of convexo-concaved contour and a substantially vertically disposed lower end part 44 which depends from the housing. Each member 38 consists of an outwardly inclined downwardly disposed upper end part 45, an outset intermediate part 46 of convexo-concaved contour and a substantially vertically disposed lower end part 47 which depends from the housing. The parts 43, 46 normally seat in the grooves 35, 36 respectively. The parts 44, 47 constitute thumb and finger grips to facilitate the shifting of the latching members from the walls 25, 26 towards the partition when latching and releasing a necktie to and from the holder. The groove 35 and part 43 of a latching member 37 and the groove 36 and part 46 of a latching member 38 function similar to that referred to with respect to the groove 7 in housing 1 and the part 15 of a latching member 11 whereby when a necktie, as indicated at 48 is connected to the holder by a latching member 37 or 38, by way of example a latching member 37 it will appear as having a portion thereof clamped between wall 25 and the part 43 of member 37.

There is common to the series of latching members 37, when any one or all of such members is or are in latching position a key-operated locking means 49 therefor to prevent the surreptitious removal of a latched tie. There is common to the series of latching members 38, when any one or all of such members 38 is or are in latching position a key-operated locking means 50 therefor to prevent the surreptitious removal of a latched tie. The means 49, 50 are oppositely disposed and are supported from the partition 27 and by the side walls 23, 24. The means 49 consists of a rotatable shaft 51 mounted in bearings 75.

52 formed on and offset with respect to the lower ends of spaced vertically disposed plates 53 anchored to the lower portion of the front face of the partition 27. The shaft 51 is mounted in the lower portions of and extends from the walls 23, 24. Fixed to and bodily moving with shaft 51 is a pair of spaced endwise aligned locking members 54 of like form and each consists of an oblong plate 55 provided at its inner side with a pair of spaced endwise aligned barrels 56, 57 mounted on shaft 51 and with barrels 57 fixed to the shaft 51 by a pin 57^a disposed diametrically of the shaft and such barrel. The barrel 56 of one locking member abuts the inner face of wall 23 and the barrel 56 of the other locking member abuts the inner face of wall 24. The shaft 51 at one end extends outwardly a greater distance from wall 23 than its other end extends outwardly from the wall 24. That end of shaft 51 which extends outwardly from wall 23 has secured thereon, exteriorly of wall 23 a key receiving element 59, which in connection with the key 60 provides for the operating of the means 49 to and from locking position. The manner in which the element 59 will be formed is shown in Figure 14. The element 59 consists of a socket forming part 61 and a sleeve forming part 62. The socket provided by the part 61 is of polygonal contour and which corresponds in contour to the ward 63 of the key 60. The part 62 is mounted on and secured to the shaft 51 by the binding screw 64. When the means 49 is moved to locking position on the turning of the shaft 51 in a clockwise direction the locking members, when the latching members 37 are in latching position, will be moved to a horizontal position to engage the parts 44 of the latching member 37 and lock the latter from being shifted to an extent to release the neckties.

The locking means 50 consists of a rotatable shaft 65 mounted in bearings 66 formed on and offset with respect to the lower ends of spaced vertically disposed plates 67 anchored to the lower portion of the rear face of the partition 27. The shaft 65 is spaced from and disposed parallel to the shaft 51. The shaft 65 is mounted in the lower portions of and extends from the walls 23, 24. The shaft 65 when the locking means 50 is operated to locking position rotates in an anti-clockwise direction. The elements of the locking means 50 are similar in construction to the elements of the locking means 49. The locking members and the key receiving element of the locking means 50 are indicated at 68, 69 respectively. The socket and sleeve of element 69 are designated 69^a, 69^b Figure 14. The key 60 is common to the locking means 49, 50. The locking means 50 functions with respect to the latching members 38 in the same manner as the locking means 49 functions with respect to the latching members 37.

The partition 27 is formed centrally thereof with a vertically disposed socket 70 opening at its bottom edge for the purpose of receiving a reduced vertical extension 71 provided on the upper end of a supporting standard 72 which extends from a base 73. The standard functions to removably suspend the holder and may be of any desired length. The junction of the extension 71 with the upper end of the standard provides a shoulder 74 upon which the partition 27 is seated.

With reference to Figure 16, the form of holder shown thereby is the same as the form shown by Figure 10, with this exception that the two series of latching members 75, 76 do not merge into couplers 40 as the two series of latching members

37, 38. In Figure 16 the latching members 75 have horizontally disposed extensions 77 at their upper ends which seat on the top edge of partition 27 and the latching members 76 have horizontally disposed extensions 78 at their upper ends which seat on the extensions 77. The extensions 77 and 78 are anchored to the partition 27 by the holdfast means 79. Otherwise than as stated, the form shown by Figure 16 will be the same as the form shown by Figure 10.

The form of holder shown by Figure 17, with the exception of the latching members 80, 81 thereof will be the same as the form shown by Figure 10. The latching members 80, 81 are of like form, but oppositely disposed. Each of the latching members shown by Figure 16 is of strap-like form and includes a vertically disposed inner end part 82, a bow-shaped top part 83, an incurved outwardly directed inner intermediate part 84, an outer intermediate part 85 of convexo-concaved contour and an incurved outer end part 86 extended from the bottom of the housing. The parts 82 of the members 80, 81 are secured by the holdfast means 86^a to the front and rear faces of the partition 27. The parts 85 of the members 80, 81 function similar to the function of the parts 43, 46 of the members 37, 38 respectively. The parts 86 of the members 80, 81 function similar to the function of the parts 44, 47 of the members 37, 38 respectively. The parts 83, 84 of the members 80, 81 function similar to the parts 42, 45 of the members 37, 38 respectively. Otherwise than as stated the form of holder shown by Figure 17 will be the same as the holder shown by Figure 10.

The form of holder 104 shown by Figure 18 will be the same as the holder shown by Figure 4, with the exceptions that the front wall 105 of the holder 104 is not formed with a groove in its inner face, and that the latching members 106 of holder 104 correspond in construction and arrangement to a series of latching members 75 or 76.

The holder 107 shown by Figure 19 will be the same as the holder shown by Figure 4, with the exceptions that the front wall 108 of holder 107 is not formed with a groove in its inner face and that the latching members 109 of the holder 107 correspond in construction and arrangement to a series of the latching members 80 or 81.

It is also to be understood that instead of employing a set of independent non-connected together pairs of oppositely extending latching members for what may be termed a double holder, a unit consisting of integral pairs of latching members may be used.

What I claim is:

1. In a necktie holder, an open top and bottom housing formed of a back, a front and a pair of sides, and a series of spaced depending shiftable latching members suspended from their upper ends within the housing from the top edge of said back and having a part thereof coacting with the inner face of said front for latching a necktie to and in suspended relation with respect to the housing, said part being arranged intermediate the ends of a member and located adjacent to the lower end of the inner face of said front, said members depending from the open bottom of the housing.

2. In a necktie holder, an open front and bottom housing including a front, a back and a pair of sides, said back being of less height than said front and sides and having its top edge arranged below the top edges of said front and

sides, a series of spaced depending latching members having their upper end terminal portions secured upon the top edge of said back, said members being arranged within and depending from the bottom of the housing, each of said members having an offset part intermediate its ends coacting with a portion of the inner face of said front for latching a necktie to and in suspended relation with respect to the open bottom of the housing.

3. In a necktie holder, an open top and bottom vertical housing including a pair of wall forming parts disposed in parallel spaced relation, an upstanding shiftable one-piece resilient latching member of strap-like form fixedly secured to and disposed in depending relation with respect to one of said parts, said member extending from said part towards the other one of said parts and having an offset portion, intermediate its ends permanently tending to engage a portion of the inner face of the said other of said parts, said member depending below the said other of the said parts and having its offset portion coacting with said inner face portion for latching a necktie to and in depending relation with respect to the open bottom of the housing.

4. In a necktie holder, an open top and bottom vertical housing including a pair of wall forming parts disposed in parallel spaced relation, an upstanding shiftable one-piece resilient latching member of strap-like form fixedly secured to and disposed in depending relation with respect to one of said parts, said member extending from said part towards the other one of said parts and having an offset portion, intermediate its ends permanently tending to engage a portion of the inner face of the said other of said parts, said member depending below the said other of the said parts and having its offset portion coacting with said inner face portion for latching a necktie to and in depending relation with respect to the open bottom of the housing, said offset portion being substantially of

convex-concavo contour, and said inner face portion being substantially of concave contour.

5. In a necktie holder, an open top and bottom vertical housing including a pair of wall forming parts disposed in parallel spaced relation, an upstanding shiftable one-piece resilient latching member of strap-like form fixedly secured to and disposed in depending relation with respect to one of said parts, said member extending from said part towards the other one of said parts and having an offset portion, intermediate its ends permanently tending to engage a portion of the inner face of the said other of said parts, said member depending below the said other of the said parts and having its offset portion coacting with said inner face portion for latching a necktie to and in depending relation with respect to the open bottom of the housing, said offset portion being substantially of convex-concavo contour, and said inner face portion being substantially of concave contour and disposed in proximity to the lower end of the said other wall forming parts.

6. In a necktie holder, an open top and bottom vertical housing including a pair of wall forming parts disposed in parallel spaced relation, a plurality of spaced parallel upstanding resilient latching members fixedly secured at their upper ends to and disposed in depending relation with respect to one of said parts, the other of said parts being formed with a groove in its inner face, said members extending from that wall forming part to which they are secured toward the said other part and each having an offset curved part, intermediate its ends permanently tending to engage the wall of said groove, each of said offset parts coacting with the wall of said groove for latching a necktie to and in depending relation with respect to the open bottom of said housing, and each of said members depending from the lower end of the said other wall forming part.

HENRY W. YOUNGQUIST.
